FIG. 1.

Technical drawing of a mechanical device, likely a press or forming tool. The top view shows a base 20 with a central cavity. A top plate 20 is positioned above the base. Various components are labeled: 24, 23, 21, 22, 19, 5, 10, 9, 15, 26, 27, 25, 4, and 6. The side view shows a curved component 5 and a base 20 with a central cavity. Components labeled include 19, 24, 20, 10, 11, 9, 16, 12, 25, and 4.

UNITED STATES PATENT OFFICE.

JOHN O. FREEMAN, OF GREENVILLE, SOUTH CAROLINA.

METALLIC RAILWAY-TIE.

1,130,586.

Specification of Letters Patent.

Patented Mar. 2, 1915.

Application filed July 29, 1914. Serial No. 853,930.

To all whom it may concern:

Be it known that I, JOHN O. FREEMAN, citizen of the United States, residing at Greenville, in the county of Greenville and 5 State of South Carolina, have invented certain new and useful Improvements in Metallic Railway-Ties; and I do hereby declare the following to be a full, clear, and exact 10 description of the invention, such as will enable others skilled in the art to which it appertains to make and use the same, reference being had to the accompanying drawings, and to letters or figures of reference 15 marked thereon, which form a part of this specification.

This invention relates to metallic railway ties and has for its primary object the provision of a metallic railway tie which shall be easy to manufacture, economical and efficient.

A further object of this invention is to provide a metallic tie which shall make allowance for vibration of the rails supported thereby.

25 A further object of this invention is to provide a tie adapted to prevent the spreading of the rails.

A further object of this invention is to provide a metallic railway tie which shall be so constructed as to allow of the rails carried thereby being adjustable to gage.

With these and other objects in view this invention consists in the peculiar combination and arrangement of the various related 35 parts of a metallic railway tie as hereinafter set forth and more particularly pointed out in the appended claims.

Referring to the drawings forming a portion of this specification and wherein similar 40 reference numerals indicate similar parts wherever used: Figure 1 is a perspective view of the device, showing the rails in position thereon. Fig. 2 is a longitudinal section through one end of the tie showing the

45 rail fastening means. Fig. 3 is a transverse section on line 3—3 of Fig. 2; and Fig. 4 is a detail perspective of one end of the improved tie.

The numeral 4 designates a metallic body 50 preferably hollow and provided at either end with members 5 and 6 cast integral therewith.

Adjacent the outer end of the tie is formed a cut out portion 7 in the top thereof, said 55 cut out portion 7 having a longitudinal slot 8 communicating therewith and formed in

the side of the tie. Adapted to be inserted within the opening 7 is a member 9 formed with a projecting lip 10 adapted to engage the lower portion of the rail as shown more particularly in Fig. 2. The lower portion of the member 9 is contracted to form a relatively smaller portion 11 which is in turn enlarged to form a larger member 12, which corresponds to the shape of the slot 8. The member 9 is inserted within the cut out portion 7 with the member 12 engaging the slot 8. This member 9 is placed within the opening 7 in such position that it abuts against the rear wall 13 of the opening 7. A second member 14 provided with an outwardly and downwardly depending lip 15 is also adapted to engage the portion of the opening 7 which is not closed by the member 11 when in its proper position. The member 14 engages the space formed by the upper member 9 and the lower extension 12 thereof and abuts against the contracted portion 11, as shown more particularly in Fig. 3.

The wedge member 16 passes through the 80 hole 17 formed in the lip 15 of the member 14 and through a properly alined hole 18 formed in the opposite side of the tie member 4. The wedge member 19 is adapted to be driven between the block 5 and the rail 20 and is provided with a cut out portion having holes 22 therein for the reception of cotter pins 23 which are adapted to hold against the flange 24 of the block 5 and thus prevent accidental loosening of the wedge 25. Directly underneath the rail 20 and in a slight depression formed in the face of the tie is placed a pad 25 formed of several plies of canvas and rubber surrounded by a covering of knitted or braided fabric which will 95 allow for the necessary vibration of the rail. The construction of each end of the tie is the same as far as the members are concerned with the exception that the position is reversed.

The operation of the device is as follows:—After the rail has been set in place in any suitable road bed, the rail 20 is placed upon the pad 25 and the member 9 slid into position in the opening 7 with the lip 10 105 engaging the lower portion of the rail. The wedge member 19 is now inserted between the rail 20 and the members 5 and driven home and the cotter pins 23 inserted against the flange 24 in order that the wedge 19 will 110 not become accidentally loosened. The member 14 is now inserted in that portion of the

opening 7 left free from engagement with the member 9, the depending lip 15 thereof engaging the face of the tie member 4. The wedge member 16 is now inserted within the openings 17 and 18 where it is driven until the rail is so positioned as to be suitable for use. The installation of the second or opposed rail is the same, although it is necessary, in placing the members in this position for the second rail, that the proper gage is secured. This may be accomplished by regulating the depth to which the wedge members 19 and 16 are driven. When the wedges have been driven to the desired depth they may be held in place by means of cotter pins 26 driven through holes 27 formed in the wedges. It will thus be seen that my tie forms an efficient device for holding the rolls in position, as well as adjusting the same to gage and also provides for any vibration of the rolls.

With the present construction the parts are so constructed as to be adapted for use with any size rail.

I realize that considerable variation of the specific details of my invention as herein set forth may be resorted to without departing from the spirit of my invention, and it is not my intention to limit myself to the specific structure as herein described, but to construe the following claims as broadly as the state of the prior art will permit.

What I claim as new and desire to secure by U. S. Letters Patent, is:—

1. A tie of the class described, comprising a hollow body portion having a recess in its top wall and a communicating recess in its side wall, the latter recess extending beyond the side walls of the recess in the top wall, the body portion having an integral rail brace, a locking member formed with a reduced central portion which forms upper and lower lateral flanges, one of the upper flanges being beveled to engage the base of a rail, the locking member fitting in the recess in the top wall of the body portion and the upper and lower lateral flanges embracing the upper wall of the body portion, one side of the locking member abutting against a wall of the body portion, a filling block having a horizontal flange which passes through the recess in the side wall of the body portion and abuts against the locking member, said filling block having an outer flange which extends down and laterally from the horizontal flange to engage the outer surface of the body portion, the flange on the filling block having an opening, a wedge fitted in said opening, and an opening in the rear wall of the body portion to wedge and lock the locking member against a rail, and means for locking the wedge in position.

2. A railroad tie comprising a body portion formed in its upper wall with a recess and a communicating recess in its side wall, and a communicating recess in its side wall,

the latter recess extending laterally beyond the walls of the recess in the top wall of the body portion, a rail brace on the top of the body portion, a locking block fitted in the top recess and formed with upper and lower flanges which embrace the top wall, a filling block fitted in the recess in the side wall, said filling block abutting against the locking member, the filling block having an outer flange which extends below and beyond the sides and bottom of the block, said flange having a recess and the under surface of the block being cut away to form a wall in alignment with one of the walls of the latter recess, a wedge fitting in the recess in the flange and engaging the wall on the under side of the block, and a wall of the locking member, the opposite end of the wedge extending through an opening formed in the rear wall of the body portion, and pins passed through the opposite ends of the wedge to hold the same in position.

3. A railroad tie comprising a hollow body portion formed with a recess in its top and a communicating recess in one wall, a rail brace on the top of the body portion, a locking element fitted in the recess in the top wall, said locking element having a rail engaging flange, a filling block fitted in the recess in the side wall and abutting against the locking block, said locking block having an outer flange formed with a recess, a wedge passing through the latter recess and engaging the locking block, the opposite end of the wedge passing through a recess formed in the rear wall of the hollow body portion, means for locking the wedge in position, a second wedge engaging the rail brace and a rail, and means for locking said second wedge in position.

4. A railroad tie comprising a body portion formed in its upper wall with a recess and a communicating recess in its side wall, the latter recess extending laterally beyond the walls of the recess in the top wall of the body portion, a rail brace on top of the body portion, a locking block fitting in the top recess and formed with upper and lower flanges which embrace the top wall, a filling block fitted in the recess in the side wall and abutting against the locking block, said filling block having a recess in alignment with an opening formed in the opposite wall of the body portion, a wedge fitting in the recess and the opening in the opposite wall, and pins passing through the opposite ends of the wedge to hold same in position.

5. A railroad tie comprising a body portion formed in its upper wall with a recess and a communicating recess in its side wall, the latter recess extending laterally beyond the walls of the recess in the top wall of the body portion, a rail brace on top of the body portion, a wedge engaging the inner surface of the rail brace, said wedge acting to

bind against a rail supported on the body portion, pins to fasten the wedge in position, a locking block fitting in the top recess and formed with upper and lower flanges 5 which embrace the top wall, a filling block fitted in the recess in the side wall and abutting against the locking block, said filling block having a recess in alinement with an opening formed in the opposite wall of the 10 body portion, a wedge fitting in the recess and the opening in the opposite wall, and pins passing through the opposite ends of the wedge to hold same in position.

In testimony whereof I have signed my name to this specification in the presence of 15 two subscribing witnesses.

JOHN O. FREEMAN.
